DESIGN FOR A TIRE

Burgess Darrow, Akron, Ohio, assignor to Wing-foot Corporation, Wilmington, Del., a corporation of Delaware

Application June 7, 1935, Serial No. 57,189

Term of patent 14 years

To all whom it may concern:

Be it known that I, Burgess Darrow, a citizen of the United States, residing at 880 Hereford Drive, in the county of Summit and State of Ohio, have invented a new, original, and ornamental Design for a Tire, of which the following is a specification, reference being had to the accompanying drawing, forming part thereof.

Fig. 1 is a perspective view of a tire, a section only being illustrated in solid lines, showing my new design; and

Fig. 2 is a cross-sectional view on the line II—II of Fig. 1.

I claim:

The ornamental design for a tire, as shown.
BURGESS DARROW.
